[57] CLAIM

The ornamental design for a roller conveyor belt for curved path, as shown.

DESCRIPTION

FIG. 1 is a top plan view of a roller conveyor belt for a curved path showing my new design;

FIG. 2 is an axonometric view on a reduced scale as seen from the small radius of FIG. 1; and

FIG. 3 is an axonometric view on a reduced scale as seen from the larger radius of FIG. 1.

The rollers are partially shown in FIGS. 1, 2, and 3 for convenience of illustration, it being understood that the rollers are uniformly continuous around the belt.
